MACHINE-MADE LACE AND PROCESS OF MANUFACTURING SAME.

Application filed July 17, 1923, Serial No. 652,108, and in Great Britain March 26, 1923.

This invention relates to the manufacture of machine made lace having a purl effect.

Hitherto when purls have been made it has been necessary to employ special threads which were drawn out of the lace in order to form the purls.

According to this invention we make purls in the bars or network of any part of the lace formed by twisting together three or more threads, by dividing as it were the bar or part where the purl is required and twisting together some of the threads only while the other thread or threads are allowed to run straight for a time after which all the threads of the bar or part are twisted together again. The straight thread or threads cause the twisted threads to bunch together and thus to form a purl. Preferably the thread or threads which are thus allowed to run straight during the formation of a purl are more heavily weighted than the threads which form the purl.

The invention is illustrated by the accompanying drawing which shows how the invention is carried out on a braiding machine, that is, a machine in which each thread is carried by a separate spindle or bobbin and the spindles move around a track which is substantially circular except that the spindles can move in and out slightly so as to cross one another and thus to twist the threads together, the lace being taken up on a mandrel arranged on the axis of the track.

Figure 1 shows the movements of sixteen spindles numbered 1 to 16 and Figure 2 represents diagrammatically and to a very much enlarged scale the lace produced by the movements shown in Figure 1. The threads on spindles 1 to 8 are more heavily weighted than the threads on spindles 9 to 16 and this is illustrated in the drawing by showing the movements of spindles 1 to 8 in thicker lines than the movements of spindles 9 to 16. It will be understood that the bar lettered A—B in Figure 2 is produced by the movements of the spindles between the points *a*, *b*, of Figure 1, the threads carried by the spindles 3, 4, 11 and 12, are twisted together for the first part of that bar and then the bar is divided as it were where the purl lettered C in Figure

2 is to be produced, and from the point *c* to the point *d* the threads on spindles 11 and 12 only are twisted together while the threads on spindles 3 and 4 are allowed to run straight; from the point *d* to the point *b* the four threads are again twisted together. The result is that the straight threads on spindles 3 and 4 pull the points *c* and *d* as it were together and the threads 11 and 12 twisted together between the points *c* and *d* are bunched together to form the purl C. In a similar manner the purl E is formed by twisting together the threads 13 and 14 while the threads 7 and 8 are allowed to run straight. The other purls shown in Figure 2 are similarly produced as can be seen by comparing Figure 2 with Figure 1. In some cases we may allow one thread only instead of two threads as above described to run straight during the formation of a purl.

What we claim is:—

1. Machine made lace having purls, each of which is formed solely by a portion of the threads being twisted together in that part of the lace in which the purls occur; the remaining threads of that portion running straight; and all of the threads being twisted together after the purl. 75

2. Machine made lace having purls, each of which is formed by a portion of the threads being twisted together in that part of the lace in which the purls occur; the remaining threads of that portion being more heavily weighted and running straight; the threads being all twisted together after the purl. 85

3. A process for making a purl in machine made lace which consists solely in twisting together a number of threads for a portion of the part of the lace in which the purl is to occur, then twisting together some only of the threads, while the remainder of the threads are allowed to run straight for a time, and then twisting together all the threads. 95

In testimony that we claim the foregoing as our invention we have signed our names 100 this 29th day of June, 1923.

CHARLES WILFRED BIRKIN.
